UNITED STATES PATENT OFFICE.

AUGUSTUS HENRY JAHN, OF PITTSBURGH, PENNSYLVANIA.

VACUUM TUBE.

Application filed May 27, 1926. Serial No. 112,084.

This invention relates to improvements in electron emission devices commonly known as vacuum tubes, and the object thereof being to connect electro-magnetic coils with the grid and plate elements to set up electro-magnetic fields in addition to that of a permanent magnet for the purpose of assisting the action of the grid and plate.

Other objects and advantages of the invention will appear in the following specification, reference being had to the accompanying drawing in which:

Figure 1 is a side elevation of the improved vacuum tube.

Figure 2 is a plan view thereof.

Figure 3 is an inverted plan view of the base.

Figure 4 is a diagram illustrating the improved tube in a typical receiving circuit.

In carrying out the invention, provision is made of a glass bulb 1 from which the air is exhausted during manufacture according to well known practice. The bulb 1 is suitably mounted upon a base 2 which has four projecting prongs 3, 4, 5 and 6 to engage the contacts of a suitable mounting. These prongs in the order given represent the positive filament lead 3^a (Fig. 4), the negative filament lead 4^a, the grid lead 5^a (Fig. 4), and the plate lead 6^a.

Only a brief reference is required to identify the diagram in Fig. 4 as being largely of conventional nature. Use is made of the customary A and B batteries and a C battery may also be employed as shown if desired. The improved vacuum tube is here shown as situated in the detecting stage of a radio receiver, and any additional stages added at the right will employ a similar tube. The improved tube is capable of use other than that of a detector because it is capable of greatly amplifying the electrical signal impulses impressed thereupon. The wiring diagram in Figure 4 is mainly intended to show how the tube is situated in the conventional receiving circuit, and further specific reference to the receiving system or "hook-up" will not be necessary.

Situated within the bulb 1 is a permanent electro-magnet 7. This magnet is of familiar horse-shoe or U-shape. It is mounted in any suitable manner, a glass pedestal 8 being shown in order to disclose some kind of mounting. The magnet has north and south pole pieces 9 and 10 disposed in confronting positions and these may either be

made integrally with the yoke of the magnet or may consist of soft iron members riveted or bolted in position.

Coils 11 and 12 are wound upon the respective pole pieces 9 and 10 in directions to produce electro-magnetic fields agreeing with the field of the permanent magnet 7, when current is conducted through said coils. One end of the coil 12 is connected with the lead 5^a (Fig. 4) the other end being connected with the grid 13. The coil 12 is therefore interposed in the grid circuit. One end of the coil 11 is connected with the lead 6^a, the other end being connected with the plate 14. The coil 11 is therefore interposed in the plate circuit. Electrical current flowing through the respective coils will serve the purpose of strengthening the respective north and south poles of the permanent magnet 7 before being impressed upon either the plate 14 or grid 13.

The operation is as follows. The permanent magnet 7 produces an even or uniform magnetic flux or field when uninterrupted by external influences. The plate 14 assumes a position in front of the north pole. The grid 13 is interposed between the filament 15 and the plate 14, but the grid is disposed near the south pole 10. The plate 14 is therefore of positive potential while the grid 13 is of negative potential, but the positive potential of the plate 14 is increased by virtue of the fact that it is connected with the positive pole of the B-battery, and negative potential of grid 13 is increased by virtue of the fact that it is disposed near and in the negative magnetic flux of south pole.

Assume that an incoming signal impulse reaches the lead 5^a (Fig. 4). The signal impulse passes on to the coil 12 producing a rise of the electromagnetic field of the permanent magnet depending upon the strength of the incoming signal impulse and the consequent superimposed electromagnetic field of the coil 12. The increase or rise of the magnetic flux will affect the grid 13, increasing the negative potential thereof as the strength of the signal impulse increases.

The grid therefore becomes a more potent factor in controlling the thermionic stream of the filament 15 so that electrons are released in a greater volume with the result that louder and clearer signals can be got without distortion.

While the construction and arrangement of

the improved vacuum tube is that of a generally preferred form, obviously modifications and changes may be made without departing from the spirit of the invention or the scope of the claims.

I claim:-

1. A device of the character described comprising a plate, a filament, a grid interposed between the filament and plate, a permanent magnet producing a magnetic field in which the plate, filament and grid are situated, and a winding upon the south pole of said magnet connected with the grid for varying said field as the electrical impulses vary thereby producing changes in the potential of the grid and a winding upon the north pole of said magnet con-
- 10
- 15

nected to the plate for varying said field as electrical impulses vary thereby producing changes in potential of the plate.

2. A device of the character described comprising means for producing a permanent magnetic field, a filament situated in said field for producing a thermionic stream, a plate constituting a target by which said stream is intercepted, a grid interposed between the filament and plate, and electrode-magnetic means connected with the grid being operable by varying electrical impulses to superimpose an electro-magnetic field upon said permanent magnetic field and thereby vary the potential of the grid to variably control the flow of said stream.
